INFANT NURSING BOTTLE

Tony Apilado, 28 W. 89th St.,
New York, N.Y. 10024

Filed Jan. 23, 1975, Ser. No. 543,502

Term of patent 14 years

Int. Cl. D9—01; D24—04

U.S. Cl. D83—8 A

FIG. 1

FIG. 2

FIG. 3

FIG. 4

FIG. 5

FIG. 1 is a front view of an infant nursing bottle showing my new design;

FIG. 2 is a right side view of an infant nursing bottle;

FIG. 3 is a rear view of an infant nursing bottle;

FIG. 4 is a top plan view of an infant nursing bottle; and

FIG. 5 is a bottom view of an infant nursing bottle.

I claim:

The ornamental design for an infant nursing bottle, as shown.
